UNITED STATES PATENT OFFICE.

JOSIE M. BROWER, OF BARTLESVILLE, OKLAHOMA.

MOP.

1,156,750.

Specification of Letters Patent. Patented Oct. 12, 1915.

Application filed March 22, 1915. Serial No. 16,158.

To all whom it may concern:

Be it known that I, JOSIE M. BROWER, a citizen of the United States, residing at Bartlesville, in the county of Washington 5 and State of Oklahoma, have invented certain new and useful Improvements in Mops; and I do declare the following to be a full, clear, and exact description of the invention, such as will enable others skilled in the 10 art to which it appertains to make and use the same.

This invention relates to improvements in mops and more particularly to dish mops.

The primary object of the invention is to 15 so construct a mop that it can be effectively and conveniently wrung without wetting the hands or touching the cloth or mop head with the hands.

Another object of the invention is to provide a two part mop handle the members of 20 which are held together by friction and yet may be readily separated for wringing the mop.

With these and other objects in view, the 25 invention consists of certain novel features of construction, and the combination and arrangement of parts as will be more fully described and claimed.

In the accompanying drawings: Figure 1 30 represents a side elevation of a mop constructed in accordance with this invention in closed position ready for use; Fig. 2 is a perspective view with the mop in the act of being wrung, Fig. 3 is an enlarged lon- 35 gitudinal section showing the connection of the washing material with the head; Fig. 4 is an enlarged transverse section taken on the line 4—4 Fig. 1, and Fig. 5 is a similar view showing the parts in the act of be- 40 ing separated.

In the embodiment illustrated a handle 1 is shown constructed of a wooden portion or main handle 2 and a metal member or removable portion 3 adapted to partially 45 encircle and frictionally engage said member 2 at the inner end thereof adjacent the mop head. As shown the main handle 2 is provided at its inner end with a suitable head 4 formed of any suitable material, 50 strings or cord being here shown. This handle 2 which is cylindrical in form is flattened at its diametrically opposite faces adjacent the head 4 as shown at 5. These flattened faces terminates at their outer ends in shoulders 6 here shown formed about midway the length of said handle. The in-

ner ends of said flat faces 5 also terminate in shoulders 7 against which the securing cord 8 which connects the cloth to the handle abuts. These shoulders 7 with the cloth engaged therewith form stops for limiting the inward movement of the member 3.

The member 3 which constitutes one section of the handle is constructed of any suitable resilient sheet metal, preferably galvanized iron, of a length about one-third more or less of the length of the handle 2. This member 3 constitutes a concavo-convex shell-like casing and is in the form of a split tube which extends around about 70 three-fourths more or less of the circumference of the handle 2 when in operative position thereon. The width of the handle between the flattened oppositely disposed faces 5 is less than the distance between 75 the two edges of the slit in the member 3 to facilitate the engagement of these members. It is of course understood that in connecting these members the handle 2 is turned to position the flat faces thereof opposite the 80 edges of the slit in the member 3 so that it may be readily inserted in said member 3. When this handle 2 is thus inserted in the member 3, it is given a quarter turn to bring 85 the wider rounded portion of said handle in engagement with the side walls of the member 3 so that the side edges thereof will frictionally engage therewith and thus securely hold the members in connected relation.

The free end of the cloth or cord 4 which constitutes the mop proper is secured to one end of the member 3 in any suitable manner, it being here shown secured by brads. Thus it will be observed that this cloth connects the two members 2 and 3 when disengaged from each other, as shown in Fig. 2, and to wring the cloth one member is grasped in one hand and one in the other and twisted in opposite directions, thereby forcing out the water. After it has been wrung, the members 2 and 3 are engaged as above described and the mop is again ready for use with the cloth doubled to form a proper washing element.

I claim as my invention:

1. In a mop the combination of a main handle, a removable concavo-convex shell-like member partially encircling and frictionally engaging said main handle, and a dish cloth connected to one end of each of said members.

2. In a mop, the combination of a cylindrical main handle, a resilient longitudinally split tubular member adapted to spring around and encircle said main handle for holding them in operative engagement, and a dish cloth connected to one end of each of said members.

3. In a mop the combination of a cylindrical main handle having a flattened face, 10 a longitudinally split tubular portion encircling said main handle at the flattened portion thereof, and a dish cloth connected to one end of each of said members.

4. In a mop the combination of a cylind-

rical main handle having flattened diametrically opposite faces, a longitudinally split spring metal tubular member for engagement with said flattened handle member, and a dish cloth connected to one end of each of said members.

In testimony whereof I have hereunto set my hand in presence of two subscribing witnesses.

JOSIE M. BROWER.
